DESIGN FOR A SPEAKER CASING

Edward E. Collison, Indianapolis, Ind., assignor to
Homer E. Capehart, Washington, Ind.

Application February 24, 1941, Serial No. 99,183

Term of patent 7 years

To all whom it may concern:

Be it known that I, Edward E. Collison, a citizen of the United States, residing at Indianapolis, Marion County, Indiana, have invented a new, original, and ornamental Design for a Speaker Casing, of which the following is a specification, reference being had to the accompanying drawing, forming part thereof.

In the drawing, Fig. 1 is a perspective view of

a speaking casing, showing my new design. Fig. 2 is a top plan view, and Fig. 3 is a bottom plan view.

The back of the speaker casing is plain.

I claim:

The ornamental design for a speaker casing, as shown and described.

EDWARD E. COLLISON.
